UNITED STATES PATENT OFFICE.

JOHN F. O'CONNOR, OF CHICAGO, ILLINOIS, ASSIGNOR TO WILLIAM H. MINER, OF CHAZY,
NEW YORK.

DRAFT-RIGGING.

1,300,461.

Specification of Letters Patent. Patented Apr. 15, 1919.

Application filed January 2, 1917. Serial No. 140,035.

To all whom it may concern:

Be it known that I, JOHN F. O'CONNOR, a citizen of the United States, residing at Chicago, in the county of Cook and State 5 of Illinois, have invented a certain new and useful Improvement in Draft-Rigging, of which the following is a full, clear, concise, and exact description, reference being had to the accompanying drawings, forming a 10 part of this specification.

This invention relates to improvements in draft rigging.

The object of the invention is to provide a high capacity spring gear having a graduated action and with all the parts compactly arranged.

A further object of the invention is to provide a draft gear having a plurality of shock absorbing units arranged in parallel with 20 means for utilizing a part only of said units for a predetermined portion of the entire stroke and then utilizing all of the units for the remainder of the stroke.

In the drawing forming a part of this 25 specification, Figure 1 is a central vertical longitudinal section of a draft rigging showing my improvements in connection therewith. Fig. 2 is a horizontal sectional view taken substantially on the line 2—2 of Fig. 30 1. Fig. 3 is a transverse, vertical sectional view taken substantially on the line 3—3 of Fig. 1. Fig. 4 is a perspective view of one 35 of the auxiliary followers employed with said arrangement. Figs. 5 and 6 are views corresponding respectively with Figs. 1 and 4, but illustrating another embodiment of the invention.

In said drawing and referring first to the 40 structure illustrated in Figs. 1 to 4, 10—10 denote center or draft sills of a railway car to which are secured stop castings having rear stop shoulders 11, front stop shoulders 12 and corresponding limiting stop shoulders 13 and 14. The draw bar 15 is operatively 45 connected to the draft gear proper, herein-after described, by a horizontal yoke 16, the latter having a coupler key connection 17 with the draw bar.

The improved gear, as shown, comprises 50 a main front follower which, for convenience in assembling, is composed of an upper member 18 and a lower member 18^a; a rear follower also composed of an upper member

19 and lower member 19^a; a front auxiliary follower 20; a rear auxiliary follower 21, 55 and triple shock absorbing units in the form of three springs 22, 23 and 24 arranged with their axes parallel and one above the other. Each of said springs preferably consists of an outer, heavy coil and an inner nested 60 coil, the latter being mounted on suitable bosses on the inner face of the followers. The upper and lower springs 22 and 24 directly engage the main followers, the upper spring 22 engaging the portions 18 and 19^a 65 and the lower spring the portions 18^a and 19^a of said followers. The central spring is seated upon inward extensions 20^a and 21^a, respectively of the auxiliary followers, which extensions 20^a and 21^a pass between 70 the upper and lower portions of each of the main followers. Each of the extensions of the auxiliary followers is provided at its inner end with upwardly and downwardly extended flanges 25—25 that overlap the adjacent portions of the main followers and thus limit the outward movement of the auxiliary followers with respect to the main followers. As clearly shown in Fig. 1, the auxiliary followers 20 and 21 80 are normally spaced a predetermined distance from the main followers and in actual practice this distance will approximate one inch for those types of gears having a total movement of three inches. All of the parts of 85 the gear are supported by means of a detachable saddle plate 26 bolted to the lower flanges of the sills and it will be seen that the gear can be readily taken down without removing the draw bar by first taking off the saddle plate, then withdrawing the lower members 18^a and 19^a of the main followers with 90 the spring 24, then withdrawing the auxiliary followers with the central spring 23, then withdrawing the yoke downwardly after first removing the coupler key 17, and finally withdrawing the upper portions of 95 the main followers together with the upper spring 22.

The operation is as follows: Upon inward movement of the draw bar, the front auxiliary follower 20 will be forced inwardly for the predetermined preliminary movement, thus compressing the central spring 23 while the upper and lower springs 22 105 and 24 remain inactive. When the front

- auxiliary follower engages the front main follower, it is apparent that all three springs will thereafter be compressed simultaneously until the full stroke is accomplished.
- 5 Under draft, the front auxiliary and main followers remain stationary and the rear auxiliary follower 21 will first be moved, thus compressing the central spring until said front auxiliary follower engages the 10 rear main follower. Thereafter all three springs will be compressed simultaneously until the limit of the draft stroke.
- In the construction illustrated in Figs. 5 and 6, the arrangement of sills and stops is substantially the same as that shown in the other figures. In this form, the front and rear main followers are formed in separate portions 118 and 118^a and 119 and 119^a, in order to accommodate the horizontal yoke 116 therebetween, said yoke being also keyed to the draw bar. In this construction, the auxiliary followers 120 and 121 instead of extending through the main followers as in the other construction over-lap the main followers and for this purpose are provided with upper and lower inwardly directed extensions 120^a and 121^a, respectively. At their inner ends, each of said extensions 120^a and 121^a is provided with a vertically extending flange 125 that over-laps the adjacent element of the main follower. The upper and lower spring 122 and 124 are seated against the extensions 120^a and 121^a of the auxiliary followers, whereas the central spring 123 is directly seated on the main followers. As in the construction illustrated in Figs. 1 to 4, the auxiliary followers are normally separated from the main followers a predetermined distance.
- 40 The operation of the construction illustrated in Figs. 5 and 6 is as follows: Upon inward movement of the draw bar, the front auxiliary follower 120 will be moved inwardly thus compressing simultaneously the upper and lower springs 122 and 124. After the predetermined preliminary movement has been obtained and said auxiliary follower engages the front main follower, it is apparent that all three springs will be compressed simultaneously for the remainder of the stroke. The action under draft will be similar and detailed description thereof is not deemed necessary.

From the preceding description, it will be seen that I have provided a draft gear of high capacity and having a graduated easy action. Furthermore, the arrangement of shock absorbing units is such that the same may be employed in cars having standard sill spacing and the usual spacing between front and rear stops, thus giving a gear of compact arrangement.

I have herein shown and described what I now consider the preferred manner of carrying out my invention, but the same is merely

illustrative and I contemplate all changes and modifications that come within the scope of the claims appended hereto.

I claim:

1. In a draft rigging, the combination with stop members, of main followers coöperable with said stop members, auxiliary followers slidable with respect to the main followers and extending forwardly and rearwardly thereof, respectively, and a plurality of shock absorbing units interposed between the main and auxiliary followers, certain of said units being actuated directly by the auxiliary followers and the others by the main followers and integral coöperating means on each set of main and auxiliary followers to limit relative separation thereof. 70
2. In a draft rigging, the combination with draft sills and front and rear stops mounted thereon, of a draw bar, a horizontal yoke, main followers coöperable with said stops, said main followers being formed in upper and lower sections disposed above and below said yoke, an auxiliary follower associated with each main follower, and a plurality of shock absorbing units interposed between said followers, the auxiliary followers having limited movement independently of their corresponding main followers and adapted to actuate a part only of 80 said units during said limited movement while the remainder of the units are inactive, all of said units being simultaneously operated after the independent movement of the auxiliary followers. 85
3. In a draft rigging, the combination with draft sills having front and rear stops thereon, of main followers coöperable with said stops, each main follower comprising an upper and a lower member, an auxiliary follower associated with each main follower and having a limiting sliding movement independently thereof, and triple arranged springs interposed between said main and auxiliary followers, one of said springs being engaged by the auxiliary followers, another by both upper main follower members and the third by both lower main follower members. 95
4. In a draft rigging, the combination with draft sills having front and rear stop members, of main followers coöperable with said stop members, each main follower comprising an upper and a lower member, an auxiliary follower associated with each main follower and independently movable thereof for a predetermined distance, a shock absorbing unit in direct engagement with the auxiliary followers, and a pair of shock absorbing units in direct engagement with 105 the main followers. 110
5. In a draft rigging, the combination with draft sills having front and rear stops thereon, of main followers coöperable with said stops, a pair of springs interposed be- 120
6. In a draft rigging, the combination with draft sills having front and rear stops thereon, of main followers coöperable with said stops, a pair of shock absorbing units in direct engagement with 125 the main followers. 130

tween said main stops and directly engaging the latter, said springs being located one above the other, an auxiliary follower associated with each main follower and slideable 5 independently thereof for a predetermined distance, and a spring interposed between the auxiliary followers and directly engaging the latter, said last named spring being

operated independently of the other two springs when the auxiliary followers are 10 moved relatively to the main followers.

In witness that I claim the foregoing I have hereunto subscribed my name this 29th day of Dec. 1916.

JOHN F. O'CONNOR.
